(57) CLAIM

I claim the ornamental design for a hand held massager, as shown and described.

DESCRIPTION

FIG. 1 is a front perspective view of a hand held massager. FIG. 2 is a front elevation view of the hand held massager illustrated in FIG. 1.

FIG. 3 is a rear elevation view of the hand held massager illustrated in FIG. 1.

FIG. 4 is a top view of the hand held massager illustrated in FIG. 1.

FIG. 5 is a bottom view of the hand held massager illustrated in FIG. 1.

FIG. 6 is an elevation view of the right side of the hand held massager illustrated in FIG. 1; and,

FIG. 7 is an elevation view of the left side of the hand held massager illustrated in FIG. 1.

The dashed lines in various figures are for illustrative purposes only and form no part of the claimed design.
